UNITED STATES PATENT OFFICE.

GEORGE H. ASIRE, OF SOUTH BEND, INDIANA.

STEAM-BOILER.

SPECIFICATION forming part of Letters Patent No. 410,394, dated September 3, 1889.

Application filed April 16, 1888. Serial No. 270,881. (No model.)

To all whom it may concern:

Be it known that I, GEORGE H. ASIRE, a citizen of the United States, residing at South Bend, in the county of St. Joseph and State 5 of Indiana, have invented a certain new and useful Improvement in Steam-Boilers, which is fully set forth in the following specification, reference being had to the accompanying drawings, in which—
10 Figure 1 is a central longitudinal sectional view of a steam-boiler embodying my invention; Fig. 2, a front elevation of the same, a portion being broken away to show the internal construction; Fig. 3, a rear elevation, a portion of the rear wall being broken away 15 to show the internal construction; and Fig. 4, a side elevation.

Like letters refer to like parts in all the figures of the drawings.
20 My invention relates to steam-boilers, and more particularly to that class known as "water-tube" boilers, and has for its object to provide a construction whereby rapid evaporation of the water can be obtained by reason of a free circulation of the water and a 25 large heating-surface thoroughly exposed to the action of the burning gases.

To these ends my invention consists in certain novel features, which I will now proceed 30 to describe, and will then particularly point out in the claims.

In the drawings, A represents the inclosing brick-work of the furnace, provided with the usual front A' and grate-bars a, the rear ends 35 of which rest upon a transverse fire-wall a'. B represents the steam and water drum, which is preferably cylindrical in shape and set transversely in the top of the brick-work A above the grate-bars, the lower half of said 40 steam-drum being within the combustion-chamber formed within the brick-work A. A steam-supply pipe b leads from the top of the steam-drum B in the usual manner. In front of the said steam-drum there is arranged 45 within the combustion-chamber a transverse water-chamber B', connected to the steam-drum B by a central pipe b'. This water-chamber is preferably angular in form, its front and bottom walls being inclined to correct 50 respond to the inclination of the water-tubes, and it being provided near its rear lower edge with a downwardly-extending water-leg B².

At the rear of the steam-drum B there is arranged within the combustion-chamber a transverse water-chamber B³, connected to the steam-drum B by means of a central pipe b². This water-chamber is also preferably angular in shape and of somewhat smaller dimensions than the water-chamber B', its rear and bottom walls being inclined to correspond to the inclination or slope of the water-tubes. At the rear of the combustion-chamber there is arranged near the bottom thereof and supported upon a bridge-wall a² a lower water-chamber B⁴, extending transversely of the combustion-chamber and preferably rectangular in shape, it being inclined to correspond to the inclination of the water-tubes and being provided with an upwardly-projecting water-leg b³ at its front. Above this water-chamber there is arranged another water-chamber B⁵, also preferably rectangular in shape and similarly inclined, it being connected to the water-chamber B⁴ by means of circulating-tubes b⁴ at each side, said tubes passing through the brick-work A and being arranged outside of said brick-work, except where they pass through the same and enter the combustion-chamber to connect with the water-chambers. The tubes are arranged in two groups—a lower or main group C and an upper or auxiliary group B—the two groups being separated by means of a baffle-plate E, which extends from the water-chamber B³ to the water-chamber B⁵, as clearly shown in Fig. 1 of the drawings. It will be observed that the baffle-plate E thus extends the entire length of the upper group of tubes, the water-chamber B³ forming a continuation at the front of said baffle-plate, and the water-chamber B⁵ forming a continuation at the rear; and since the space above the water-chamber B³ is closed in the manner hereinafter described the direction of the gases is completely reversed and all portions of both groups of tubes thoroughly heated, as herein-after set forth. All the water-tubes are inclined downward from front to rear, those of the lower group serving to connect the water-chamber B' with the water-chamber B⁴, and those of the upper group serving to connect the water-chamber B³ with the water-chamber B⁵. The two upper rows of tubes c of the lower group C are connected at their front

ends directly to the water-leg B^2 of the water-chamber B' by means of suitable screw or other joints, their rear ends being connected to the water-chamber B^4 by means of short tubes c' , arranged at right angles to the long tubes c and entering the top of said water-chamber, to which they are connected in any suitable manner. The lower rows of tubes c^2 of the lower group C are connected at their rear ends directly to the water-chamber B^4 or its water-leg b^3 , while their front ends are connected to the water-chamber B' by means of short tubes c^3 , arranged at right angles to the long tubes c^2 and entering the bottom of the water-chamber B' , as shown in Fig. 1. The tubes d of the upper group D are connected at their front ends directly to the water-chamber B^3 , their rear ends being connected to the water-chamber B^5 by means of short tubes d' , arranged at right angles to the long tubes D , and entering the said water-chamber at the top.

It will be observed that each water-tube consists of two portions—a long tube and a short tube—arranged at right angles thereto. The connection between these two portions is effected by means of a four-way coupling or union F, having two passages arranged at right angles and passing entirely through the same, two of the orifices thus formed receiving the ends of the long and short pipes, respectively, while the two orifices opposite the ends are closed by means of screw-plugs f. It will also be observed that the tubes of each group are so arranged that the tubes composing each horizontal series, instead of being immediately below the tubes of the series above them, are arranged beneath the spaces separating the tubes of said upper series. In other words, the arrangement of the tubes is alternate instead of coincident. This arrangement enables me to carry each individual tube clear through to the front or rear, as the case may be, without displacing or deflecting the short tubes, which serve to connect the long tubes to the water-chambers. Each individual tube is thus readily accessible for cleaning, either at one end of the apparatus or the other, both so far as its long and short portions are concerned, and all the tubes are substantially of the same length and capacity.

On the top of the fire-wall a' there is arranged, at right angles to the tubes of the lower group, a transverse baffle-plate G, extending upward to the top of the said tubes, which latter pass through the said plate. In the rear of this baffle-plate and about half-way between the same and the rear end of the tubes there is arranged another baffle-plate G', extending transversely across the combustion-chamber and downward from the baffle-plate E to the lower portion of the said tubes.

The main circulating-tubes H are connected to the water-chamber B^4 at the ends thereof, and, passing outward through the brick-work A, extend upward and forward outside of the same to a point opposite the ends of the steam-

drum B, at which point they pass inward through the brick-work and open into the said drum, passing through the ends thereof at a point near the bottom of the drum, as indicated in Fig. 1 of the drawings. These pipes are two in number, being arranged one on each side of the apparatus and outside of the combustion-chamber, except at those points where they enter the same to connect with the steam-drum and water-chamber.

I represents the smoke-flue, which leads from the combustion-chamber at a point immediately above the front ends of the upper group of water-tubes, a small baffle-plate i being arranged transversely of the combustion-chamber between the top thereof and the top of the water-chamber B^3 immediately in front of the smoke-flue.

The apparatus thus constructed operates in the following manner: It will be observed that the burning gases from the fuel placed upon the grate-bars a pass first directly upward and heat not only the upper end of the lower group of pipes, but also the steam-drum and the water-chambers B' and B^3 at the front of the combustion-chamber. These gases then pass over the baffle-plate G and heat the middle portion of the lower group of tubes, then under the baffle-plate G, after which they heat the lower portion of the lower group of tubes, and, passing around the end of the baffle-plate E, heat the upper group, and pass thence into the smoke-flue, following throughout the course indicated by the arrows in Fig. 1. By dividing the water-tubes into two groups separated by the baffle-plate E, I am enabled to expose the said tubes much more thoroughly to the action of the burning gases and obtain a greater heating-surface and a more thorough and quick evaporation of the water. This is also facilitated by the use of the circulating-tubes connecting the several water-chambers and the steam-drum, which, by promoting a free circulation of the water, materially increase the efficiency of the apparatus. The construction of each tube in two sections connected at an angle to each other permits free expansion and contraction of the said tubes, and the employment of the four-way joint or union at the point of connection of the sections permits each section of each tube to be readily accessible for cleaning or inspection by simply removing the screw-plug opposite the end of the same.

It is obvious that various modifications in the details of construction may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. The combination, with the steam-drum B, of the transverse water-chambers B' and

B³ connected thereto, the water-chambers B⁴ and B⁵, arranged at the rear of the combustion-chamber, the inclined groups C and D of water-tubes, connecting, respectively, the 5 chambers B' B⁴ and B³ B⁵, and the circulating-pipes b⁴ and H, connecting the rear water-chambers with each other and with the steam-drum, substantially as and for the purposes specified.

10 2. The combination, with the water-chamber B', having water-leg B², and the water-chamber B⁴, having water-leg b³, of the water-tubes c, connected to the water-leg B², the short tubes c', arranged at right angles thereto and connected to the water-chamber B⁴, the water-tube c², connected to the chamber B⁴ and its water-leg b³, and the short tubes c³, arranged at right angles thereto and connected to the water-chamber B', substantially 15 as and for the purposes specified.

3. The combination, with the upper and lower water-chambers, of the water-tubes connecting the two, and each consisting of a long inclined tube and a short tube arranged at 20 right angles thereto, the horizontal series of said tubes being alternately arranged, as described, so that each tube extends clear through to the front or rear, substantially as and for the purposes specified.

4. The combination, with the steam-drum, 30 of the lower group C of water-tubes, above the front portion of which the steam-drum is arranged, the upper or auxiliary group extending rearward from the steam-drum, a baffle-plate arranged between the two groups 35 and extending from the front water-chamber to the rear water-chamber of the upper group, and a second baffle-plate closing the space between the front water-chamber of the upper group and the casing, substantially as 40 and for the purposes specified.

5. The combination, with the water-tubes, each composed of two sections arranged at right angles to each other, said tubes being arranged in alternate horizontal series, so 45 that each tube extends clear through to the front or rear, of the four-way unions or couplings connecting the two sections of each tube and provided with screw-plugs to close the apertures opposite the ends thereof, substantially as and for the purposes specified.

GEORGE H. ASIRE.
